MACHINE FOR HANDLING FOUNDRY MOULDS
Jean-Jacques Gerardin, Clos-Jean, Pont-a-Mousson,
France, assignor to Compagnie De Pont-a-Mousson,
Nancy, Meurthe-et-Moselle, France, a corporation of
France

Filed Nov. 29, 1961, Ser. No. 153,587
Claims priority, application France, Nov. 22, 1960
4 Claims. (Cl. 22—10)

The present invention relates to the handling of foundry moulds of the metallic type having two parts capable of being united and separated and more particularly to the transferring of these moulds to the different working stations and their mechanical opening and closing by the separation and union of said two parts respectively.

By "foundry mould" is meant in the ensuing description not only moulds for casting various parts and objects, but also core boxes for casting cores forming part of said moulds.

In mechanized foundries, the handling apparatus for the moulds are subjected to severe service conditions: erosion by the projections of sand due mainly to the use of blowing machines, alternating expansions and shrinkages in the regions of production of heat, such as in the pouring stations or the ovens and outside said regions. This results in considerable wear and high maintenance costs. These working conditions are particularly harmful to the mould opening and closing mechanisms. These mechanisms generally comprise guiding slides and other relatively fragile elements and are in known machines controlled so as to follow the movements of the mould transfer device and consequently undergo material variations in temperature due to successive passages through stations such as the pouring and drying stations at which high temperatures prevail and a station or stations at room temperature, in particular the station at which the casting or core is removed from the mould or core box.

The object of the invention is to provide a machine for handling metal moulds having two parts separated by a joint plane, said machine being of the type comprising a mould transfer mechanism by means of which each mould is caused to pass through and stop at each one of a series of successive stations and opening and closing mechanism for said moulds and being so improved as to remedy the afore mentioned disadvantages of known machines by avoiding subjecting the opening and closing mechanism to any large variation in temperature and eliminating any rubbing surface capable of undergoing rapid wear thereby imparting to said improved machine great strength.

This result is obtained owing to the fact that in said improved machine the mould opening and closing mechanism disposed at a fixed station corresponding to the casting or core removal station, is adjacent and associated with the transfer mechanism from which it is independent and is adapted to firmly take hold of each mould arriving at said fixed station, open it and close it and finally return it in the closed condition to said transfer mechanism.

In one embodiment of the invention, the transfer mechanism for the moulds comprises at least one vertical rigid support which is movable relative to the stand of the machine as a function of a predetermined path of movement of the moulds, and which is provided with at least one mould hooking element, said element having such orientation that the joint plane between said two parts of the mould is vertical and normal to said path, and the mould opening and closing mechanism comprises two devices carried by the stand tangent to said path and adapted to take hold of each one of said parts of the mould to be opened, one of said devices being fixed relative to a given point in said path whereas the other is movable relative

2

to the first device in a direction substantially tangent to the path at this point.

Another object of the invention is to provide a metal mould (a proper mould or core box) having two parts united in a joint plane, said parts comprising means for interconnecting said parts, and one of said parts comprising means for hooking to the transfer mechanism of a mould handling machine, whereas said two parts are provided with lugs by means of which they are taken hold of by an opening and closing mechanism of the machine.

Further features and advantages of the invention will be apparent from the ensuing description, with reference to the accompanying drawings to which the invention is in no way limited.

15 In the drawings:

FIG. 1 is a diagrammatic elevational view of the machine according to the invention provided for handling moulds constituted in this case by core boxes, the front uprights of the stand having been removed;

20 FIG. 2 is a side elevational view of the machine shown in FIG. 1;

FIG. 3 is a partial horizontal sectional view taken along line 3—3 of FIG. 1;

25 FIG. 4 is a partial view similar to FIG. 1, the machine being in the position for raising a mould;

FIG. 5 is a partial view similar to FIG. 3, the machine being in the position for opening a mould;

30 FIG. 6 is a partial horizontal sectional view taken along line 6—6 of FIG. 5, and

FIG. 7 is a partial horizontal sectional view of a modification of the hooking means for hooking the moulds to the transfer device.

In the embodiment shown in FIGS. 1—6, the invention is applied to the manufacture of cores produced by means of a mixture of sand and resin which must be hardened by application of heat, and more particularly to the handling of moulds (M) constituted, for example, by core boxes of metal type having two parts *a* and *b* located with respect to each other by cylindrical dowels *c* the axis of which latter is contained in the joint plane of the two parts.

40 The moulds M (the cores boxes) are adapted to travel through a horizontal circular path whose centre is situated on a vertical axis X—X and pass in succession through M¹ (FIGS. 1 and 3) in a moulding station I (for example a blowing machine of known type, not shown), then, through M² to M³ in a drying oven II (the interior of the oven being shown in dot-dash lines) to M⁴ in a casting or core removal station III.

45 The machine comprises, disposed on a stand A: a transfer mechanism B for passing each mould in succession through the stations I to III, located at the station III, a mechanism C for opening and closing each mould which arrives at this station and a retractable abutment device D for stopping the mould to be opened precisely below the mechanism C.

50 The stand A comprises a base I, rigid uprights 2 and an upper bolster 3.

The transfer mechanism B is mounted on the base 1 and comprises a rigid support constituted by a vertical pivot 4 having an axis X—X about which the moulds are adapted to describe a circular path.

55 A number *n* of horizontal mould support means or bars 6 are laterally connected to the pivot 4 through the medium of lugs 5. The pivot 4 comprises, spaced a certain distance below the lugs 5, a support or bearing plate 7 having the same number *n* of sides. In the presently-described embodiment, the number *n* of bars and sides of the plate 7 is equal to four.

60 The pivot 4 and the bars 6 and the plate 7 constitute the transfer device for transferring the moulds M. Four of the latter, namely M¹, M², M³, M⁴ (FIG. 3) are mounted in the form of a cross on the pivot 4. The part *a* of

each mould is adapted to remain fixed during the opening of the mould at station III and is provided in the upper part of its side directed toward the pivot with a pair of hooking means or of ears 8 and 9 which hook on one of the support bars 6 of the pivot. The other part b of the mould is adapted to be displaced in the course of opening the mould and does not comprise hooking ears for the bar 6. The ear 9 of the part a is disposed on the part a in the manner of a cantilever so as to face or overlap the part b and thereby hold the mould in equilibrium or balance in opposition to a tilting torque about the ear 8. When the mould is closed, its part b is maintained in position vertically by the part a through the medium of dowels c and hooks and pins described hereinafter, and the two parts bear at the lower part of their sides against the square plate 7 of the pivot 4.

Half way up the sides of the moulds, the latter comprise releasable fastening means for interconnecting the parts a and b, the fastening means comprising a pair of hooks 10 pivoted to the part a at 11 and with which are associated pins 12 fixed to the movable part b and on which the hooks 10 hook. Each hook 10 is provided at one end with a flat face 13 (FIG. 2), to which pressure is applied for retracting the hook from the pin 12 and is extended at its other end in the form of an actuating lever 14 having such length as to project from the part a and render the hook accessible to the operator. The lever renders accessible, in particular that one of the two hooks 10 disposed toward the interior of the machine, that is, near the pivot 4.

The parts a and b of each mould are provided at the upper part of their sides with a pair of flat suspension lugs or handles 17.

The mould opening and closing mechanism C consists, at the casting removal station III, of two devices secured to the bolster 3 in such manner that one of the devices (P) is located above the part a of the mould in the position M⁴ and the other device is movable in translation relative to the first device between a first position Q in which it is alongside the first device P and is above part b of the closed mould M⁴ (FIGS. 2 and 3), and a second position Q¹ (FIGS. 5 and 6) in which the device is separated from the first device in a direction Y-Y (FIG. 6), which direction is tangent to the circular path Z-Z of the moulds, and substantially horizontally under the effect of an actuating device R.

The fixed device P comprises a plate 18 suspended by a pair of rigid pillars 19 from the bolster 3 so as to be disposed above the part a of the mould in position M⁴, there being a vertical clearance j (FIG. 1) between the plate 18 and the closed mould when the latter rests, through the medium of the part a on the corresponding support bar 6, and, through the medium of the two parts a and b against the plate 7. Secured to the top of the plate 18 is a jack or ram 20, for example, a pneumatic ram having a double-acting piston the vertical piston rod of which terminates at its upper end in a fork 21 pivoted to a stirrup member 22 the arms of which are so shaped as to encompass the opposite end faces of the part a of the mould M⁴ and terminate in hooks 23 (FIG. 1) adapted to engage under the lugs 17 of the part a.

The other device, movable between the positions Q (FIGS. 2 and 3) and Q¹ (FIGS. 5 and 6), comprises a plate 24 suspended by means of two pairs of flexible strips 25 from the bolster 3 in such manner that, in the position Q, the plate is disposed above the moving part b of the mould M⁴ on the same level as the fixed plate 18. Secured to the moving plate 24 is a jack or ram 26 identical to the ram 21 and adapted to actuate, through the medium of a fork 27, a stirrup member 28 identical to the member 22 and performing for the part b the same function as the member 22 performs for the part a.

The rams 20 and 26 are fed (FIG. 2) by a pair of pipes 29-30 and 29a-30a as shown. The pipes 29 and 29a are connected to a main supply pipe 31 and the

75 pipes 30 and 30a to a second main supply pipe 32. The pipes 31 and 32 constitute two ways of a four-way tap 33. The two other ways of the tap are constituted by a pipe 34 supplying the fluid under pressure, and a discharge pipe 35.

The moving plate 24 further comprises a pair of lugs 36 pivoted at 37 to the actuating device R, in the presently-described embodiment to the rod 38 of the piston of a double-acting pneumatic ram 39 adapted to shift the movable device from the position Q to the position Q¹. The ram R is pivotally suspended in a substantially horizontal position by means of a pair of lugs 40 at the lower end of a rigid pillar consisting of two coupled arms 41 (FIGS. 2, 5 and 6) suspended from the bolster 3. It is supplied by a pair of pipes 42 and 43 (FIGS. 2 and 5) constituting two ways of a four-way tap 44 whose two other ways are constituted by a pipe 45 supplying fluid under pressure and a discharge pipe 46.

The device D for putting the mould in the position M⁴ at the casting or core removal station comprises, fixed to the base 1, a support 47 (FIGS. 1 and 3) to which is pivoted a retractable abutment member 48 for stopping the core boxes or moulds at M⁴ immediately below the devices P, Q of the mould opening mechanism. This abutment member is constituted by a bell-crank pivoted at the apex of the crank. One of the ends of this crank performs the function of an abutment for the mould whereas the other end acts as an operating lever for the operator.

The machine operates in the following manner:

Let it be supposed that the pivot 4 is stationary and that a core box or mould has been stopped at M⁴ by the abutment member 48 of the device D at the casting removal station III in the position shown in FIGS. 1-3. In order to open this box, the following operations are performed:

The tap 33 is first turned in such manner as to connect the fluid supply pipe 34 to the main pipe 31 and the main pipe 32 (FIG. 5) to the discharge pipe 35. As a result of this, the stirrup members 22 and 28 of the devices P and Q are raised and, in taking hold of the parts a and b under the lugs 17, they raise the mould M⁴. The raising of the mould M⁴ stops when the upper faces of the parts a and b bear under the plates 18 and 24 (FIG. 4). At this moment, the mould is suspended from the bolster of the machine through the medium of the members 22 and 28. The lower face of the mould is moreover at a level very slightly higher than that of the support plate 7 of the pivot 4 but its part a remains engaged on the corresponding support bar 6. Therefore, in this position, the plate 18 to which the part a is secured, holds the pivot 4 stationary through the medium of the ears 8 and 9 of the part a.

The hooks 10 are unhooked from the pins 12 to unlock the mould M⁴. Thereafter the abutment member 48 is retracted by the operator to the position shown in dot-dash line at 48a (FIG. 1) so as to permit opening this mould.

The four-way tap 44 is turned from the position shown in FIG. 2 to that shown in FIG. 5 so as to connect the pipe 43 to the supply pipe 45 and the pipe 42 to the discharge pipe 46 (FIG. 5). The ram 39 of the actuating device R then shifts the moving plate 24 from the left towards the right. As the part b of the mould M⁴ is connected to the plate 24 by the stirrup member 28, it is shifted at the same time as this plate. The shifting of the plate causes the flexible strips 25 to bend and they assume the curvature shown in FIG. 5. The separation of the part b from the part a—which separation does not take place in a horizontal plane but is accompanied by a slight raising of the part b as shown in FIG. 5 owing to the deformation of the strips 25—is made possible by the position of the dowels c whose axis is in the joint plane of the two parts a and b and any wedging is avoided.

Owing to the fact that the plate 24 moves toward the axis of suspension of the ram 39 the latter assumes a certain inclination relative to the horizontal. The shifting of the part *b* of the mould occurs until the piston of the ram 39 is at the end of its travel toward the right. At this moment the mould M⁴ is fully opened (FIG. 5).

The opening of the moulds permits, on the one hand, withdrawing the core or casting and, on the other hand, cleaning the mould and applying thereto, if desired, an insulating coating.

To close the mould, the reverse operations are effected: the four-way tap 44 is returned to the position shown in FIG. 2 and this causes the return of the piston of the ram 39 toward the left and consequently the return of the plate 24 to its initial position and the shifting of the part *b* toward the part *a* of the mould M⁴. Owing to the fact that the parts *a* and *b* are secured to the plates 18 and 24 which act as guides, and owing to the positioning of the cylindrical dowels *c* in the joint plane, the part *b* easily resumes its position and fits against the part *a*. The flexible strips 25 resume their straight shape. In order to lock the mould in the closed position, the hooks 10 are re-hooked over the pins 12.

The tap 33 is returned to the position shown in FIG. 2 and this causes the descent of the pistons in the rams 20 and 26 and the lowering of the stirrup members 22 and 28. During the downward travel of these members the mould M⁴, whose part *a* remained engaged on the bar 6, is guided by the latter and once more becomes supported on this bar and against the plate 27. When the pistons of the rams 20 and 26 are at the end of their downward travel, the hooks 23 of the members 22 and 28 release the lugs 17 as shown in FIG. 1.

The operator then exerts a thrust on the mould M⁴ so as to turn the pivot 4 through a quarter of a revolution in the direction of arrow *f* (FIG. 2) and shift the mould M⁴ from the casting removal station III to M¹ at the moulding station I, whereas the following mould M³ coming from the oven II which contains a core or other casting ready to be removed from the mould, is in turn brought to the casting or core removal station III where it is stopped by the abutment member 48 which is raised to the position shown in full line in FIG. 1. One operational cycle has finished. It is repeated thereafter in the same manner.

It can be seen that the machine according to the invention is particularly advantageous in that it is simple and strong. It has in particular no rubbing element liable to wear out. Its mould opening and closing mechanism is fixed and does not accompany the core boxes or mould inside the oven II and is not subjected to heat.

More particularly, owing to the system of hooking each mould to the support bar 6 by means of the ears 8 and 9 and its simple bearing against the plate 7, the mould is connected in a sure manner to the pivot but is easily removable therefrom to permit its raising and opening. Further, the support bar 6 and the ears 8 and 9 co-operate in the guiding of the mould and insure that it is put back into correct position on the transfer mechanism B when the members 22 and 28 descend.

Owing to the plates 18 and 24 and to the members 22 and 28 which hold the parts *a* and *b* of the mould against said plates, these two parts are firmly suspended from the bolster 3 of the stand A when the mould is opened. This combination between the plates 18 and 24 and the members 22 and 28 is just as effective as a clamp having a fixed jaw and a movable jaw while it is much lighter and takes up less space, since the movable jaw of the clamp is replaced by the members 22 and 28 terminating in the hooks 23. This combination has the further advantage of guiding the two parts *a* and *b* of the mould at the beginning of its opening and at the end of its closure.

It is, moreover, clear that the extremely simple way in which the moulds are hooked (combination of the ears 8 and 9, support bar 6 and plate 7) and the way in which

the moulds are taken hold of and guided (combination of the plates 18 and 24, members 22 and 28 and lugs 17) enable the moulds to be readily and rapidly interchanged.

If it is desired to mount on the machine moulds having another moulding print for manufacturing different castings, it is merely necessary to unhook the already mounted moulds and hook the new moulds in position, on condition of course that they have the same outside shapes. No adjustment or setting is necessary.

The manner in which the plate 24 is suspended from the bolster 3 through the medium of flexible strips 25 has the great advantage of eliminating any frictional guide means and thus greatly simplifies the construction as concerns the mounting of the plate 24. The manner in which the two parts *a* and *b* of the mould are set relative to each other by means of the dowels *c* disposed in the joint plane permits the use of these flexible strips without risk of wedging when starting the separation of the parts or bringing the latter together.

In the modification shown in FIG. 7, the support bar 6 is fixed to the pivot 4 at its middle and at one of its ends only. The part *a* of the mould has only one hooking ear 49 and the part *b* has an identical hooking ear 50 engaged on the end of the bar 6 so as to permit opening 25 the mould. The machine operates in the same manner as the previously-described machine.

Although specific embodiments of the invention have been described, many modifications and changes may be made therein without departing from the scope of the invention as defined in the appended claims.

Instead of a rotational transfer of the moulds the transfer device could be arranged to transfer the moulds in translation. Indeed the invention is applicable to production lines. In this case, the production line would have a series of rigid vertical supports corresponding to the element 4 and each provided with an upper support bar 6 and a lower bearing plate 7 which are parallel with the direction of translation of the production line so as to dispose the joint plane of the moulds in a direction perpendicular to said direction of translation. In this application, the opening and closing mechanism at the casting removal station would remain fixed and identical to the mechanism C described hereinbefore.

Having now described my invention what I claim as new and desire to secure by Letters Patent is:

1. A machine for handling metal moulds in two halves separable along a vertical joint plane, said machine comprising in combination: a stand; on said stand, a rotatable pivot adapted to stop at each one of a series of stations; a plurality of mould support means carried by said pivot, for suspending the mould halves on said pivot, the number of said support means being equal to the number of said stations; hooking means provided on each mould for hookingly engaging the support means corresponding to the mould whereby the latter is supported by the support means; a mould opening and closing mechanism mounted on said stand and disposed at a fixed station and having two devices adapted to firmly grab respectively said mould halves, each device comprising a transverse element located above the corresponding portion of the mould and mounted on said stand; a stirrup member disposed astride said transverse element and movable relative to the transverse element; each mould half having lugs and each stirrup member having hooks capable of engaging under said layer; and a double-acting jack connecting the transverse element to said stirrup member to shift the stirrup member vertically relative to said transverse element, whereby the stirrup member, in rising, applies the hooks thereof under the lugs of the corresponding portion of the mould and applies said portion against the under face of the corresponding transverse element and, in descending, returns said corresponding portion of the mould to the position in which the hooking elements are hooked on the corresponding mould support means; and reciprocating means connected to one of said devices

for selectively moving the last-named device away from and toward the other of said devices for opening and closing said moulds.

2. A machine according to claim 1, in which the device other than that connected to the reciprocating means is rigidly attached to said stand.

3. A machine according to claim 1, in which the device which is connected to the reciprocating means is suspended from the stand by elastically yieldable means in the form of spring-bands.

4. A machine according to claim 1, in which said pivot

is rigid and pivots about a vertical axis, and each of said mould support means includes lateral bearing means for the lower part of the corresponding mould, said bearing means being in the form of the edge of a plate rigidly secured to said pivot.
